(57) **CLAIM**

The ornamental design for electronic medical guide, as shown and described.

DESCRIPTION

FIG. 1 is a top view of the device.

FIG. 2 is a bottom view of the device.

FIG. 3 is a front view of the device.

FIG. 4 is a back view of the device.

FIG. 5 is a left side view of the device.

FIG. 6 is a right side view of the device; and,

FIG. 7 is a perspective view of the device.

1 Claim, 4 Drawing Sheets

FIG. 1

FIG. 2

FIG. 3

FIG. 4

FIG. 5

FIG. 6

FIG. 7
